HEEL TRIMMING MACHINES

Brian Julian Maurice Murphy and John Rose Pope, Leicester, England, assignors to United Shoe Machinery Corporation, Flemington, N. J., and Boston, Mass., a corporation of New Jersey

Original application May 23, 1955, Serial No. 510,426. Divided and this application June 20, 1956, Serial No. 592,678

3 Claims. (Cl. 12—90)

This invention relates to machines for trimming portions of partially fabricated shoes and more particularly to a heel trimming machine of the type disclosed in United States Letters Patent No. 961,752, granted June 21, 1910, on an application filed in the name of J. N. Busell and to a machine disclosed in application for United States Letters Patent Serial No. 510,426, filed May 23, 1955, of which this application is a division.

The Busell machine is provided with a crease guide or guard attachment surrounding one end of the cutting blades and is arranged to engage the crease formed between the heel and the shoe upper, frequently called the rand crease. The purpose of the crease guide is to regulate how close to the upper the heel is trimmed while preventing the blades from damaging the upper; that is, the relative positions of the crease guide and the cutter blades determine the extent to which the periphery of the trimmed heel projects beyond the periphery of the upper at the rand crease. The spacing between the blades and the shoe upper must be adjusted over a wide range to accommodate the various styles of shoes to be trimmed, and to provide for adjustment of the spacing, the periphery of the crease guide of the Busell machine is stepped to provide three concentric shoe engaging areas any one of which may be employed at one time. If finer adjustment than can be provided with the crease guide is necessary, it is obtained by adjusting the positions of the blades in the cutter head by means of a rotatable plate. Frequently, therefore, to trim a given shoe two adjustments are required necessitating considerable skill on the part of the operator.

Accordingly, an object of this invention is to provide a heel trimming machine having a single easily operated mechanism requiring a minimum of skill for varying accurately the amount the periphery of the trimmed heel projects from the periphery of the shoe upper.

Another object of this invention is to provide a heel trimming machine with improved means to vary accurately the position of a shoe relative to a heel trimming cutter without changing the location of the cutter blades.

In accordance with these objects and as a feature of this invention, the trimming machine herein illustrated is provided with a cutter head comprising a pair of ribbed clamping members between which cutting blades are removably secured, a crease guide shrouding one end of the blades and having a shoe engaging periphery adjustable relative to the cutting blades and constructed to provide minute variations in spacing between its shoe engaging periphery and the circular path in which the cutting edges of the blades rotate. By constructing the crease guide in the form of an involute, it is unnecessary to make more than one adjustment to control how close to the upper the heel of a given shoe is trimmed, the single adjustment being the rotation of the involute shaped crease guide.

The above and other features of the invention, including novel details of construction and combinations of

2

parts, will now be described with reference to the accompanying drawings and pointed out in the claims.

In the drawings,

Fig. 1 is a front elevation partly in section of the operating portion of one form of machine embodying the invention;

Fig. 2 is a plan view partly in section of the part of the machine shown in Fig. 1 with the cutting head assembly removed; and

Fig. 3 is a diagrammatic representation of the shape of a crease guide viewed from the right of the machine in the position shown in Figs. 1 and 2, but on an enlarged scale.

The heel trimming machine herein illustrated is generally similar in construction and method of operation to the machine disclosed in the aforementioned Busell Patent No. 961,752, and attention is directed to that patent for the description of parts not hereinafter described in detail.

The machine has a cutter head assembly 2 (Fig. 1) mounted in front of a dust hood 3 on the left end of a driven cutter shaft 4, journaled in a frame 6 and rotatable about an axis B. The cutter head comprises a ribbed hub member 8 fixed to the shaft 4 and a mushroom shaped ribbed member 10 fixed to a shaft 12 which passes through an axial bore in the cutter shaft 4. Threaded in the shaft 12 is a screw 14 which, when rotated in a clockwise direction, draws the ribbed member 10 toward the ribbed hub 8 to clamp a pair of cutter blades 16 therebetween, eccentric ribs (not shown) formed on the opposed faces of the members 8 and 10 engaging mating grooves formed in the blades 16 acting as guideways for the blades. The ribs and the blades 16 are similar to the parts referred to as 10 and 12, respectively, in the above-mentioned patent to Busell, although the ribs may be formed on the blades and the mating recesses in the members 8 and 10. A keyway 20 formed in the shaft 12 engages a complementary key fixed in the cutter shaft 4 to prevent relative rotation of the ribbed members 8 and 10.

Surrounding part of the ribbed hub member 8 is a top lift rest 22 and adjacent the blades 16 is a work rest 24 adjustably clamped in the machine frame 6. The top lift rest and the work rest respectively are similar in construction to the top lift rest 22 and the work rest 26 described in the Busell patent.

Cooperating with the top lift rest 22 and the work rest 24 to support and guide a shoe as its heel is presented to the cutting head is the crease guide 26 which shrouds the mushroom-shaped member 10 (Fig. 1).

The crease guide is in the form of a dished plate having a stud 30 fixed to its convex surface, the center of which stud lies on an axis C. The work engaging portion of the periphery of the crease guide is in the form of an involute and will be more fully described hereinafter. The stud 30 is supported in a bore in the enlarged right-hand end of a slide 32, and is restrained from axial movement by a pin 34 (Fig. 1) fixed in the slide and engaging a groove 36 (Fig. 2) formed in the stud and extending part way around its periphery. In order to adjust the work engaging portion of the crease guide relative to the cutting blades 16 as will be explained in more detail hereinafter, the crease guide is rotated on its axis C relative to the slide 32 but this movement is limited by the pin 34 engaging the end of the groove 36. A clamp screw 38 threaded in the slide engages the stud to enable an operator to lock the crease guide in a desired angular position. Graduations 33 marked on the crease guide assist the operator in selecting the angular position.

The main portion of the slide 32 which is cylindrical and coaxial with the stud 30 is axially adjustable in a carrier 40. A key 42 (Fig. 1) fixed in the carrier engages

a complementary keyway formed in the slide and thus prevents rotation of the slide relative to the carrier. The slide is adjusted axially in the carrier by an adjusting screw 44, threaded in the left-hand end of the slide, the screw having a knurled knob 46 and a flange 48 which engages a plate 50 fixed to the carrier. A spring 52 compressed between the knurled knob 46 and the plate 50 tends to prevent backlash developing in this mechanism and to prevent inadvertent rotation of the adjusting screw 44. Graduations (not shown) corresponding to different width cutter blades are marked on the slide to assist the operator in adjusting the crease guide to a desired position so that it just shrouds the ribbed member 10.

The carrier 40 is pivoted on a vertical stud 54 fixed in the forward end of a link 56 the rearward end of which is fixed by means of a clamp screw 58 to a vertical pin 60 journaled in bearings 62 and 64 in the frame 6. Extending rearwardly from the carrier 40 is a flange 66 having formed in it an arcuate slot 68. A link 70 is adjustably secured to the flange 66 by means of a clamp bolt 72 passing through the arcuate slot and having an enlarged head 74 engaging the lower surface of the flange. A wing nut 76 threaded on the bolt 72 enables the operator to clamp the link 70 in any position along the arcuate slot. Graduations 78 along the slot assist the operator in positioning the link 70 for a purpose to be explained hereinafter. The rearward end of the link 70 is pivoted on an eccentric portion 80 of a bolt 82 adjustably mounted in the frame 6 and secured thereto by means of a lock nut 83. The bolt 82 is in a position (see Fig. 2) forward and to the left of the pin 60.

The carrier 40, and consequently the crease guide 26, is urged to the right, as seen in Figs. 1 and 2, by means of a tension spring 84 secured to the frame 6 and to an arm 86 fixed to the lower end of the pin 60. Movement of the crease guide to the right under the action of the spring 84 is limited by an adjustable stop screw 88 threaded in the link 56 and held in adjusted position by a lock nut 90. The forward end of the stop screw abuts a portion of the frame 6.

Referring to Fig. 1, the dotted outline of a shoe is shown in position to have its heel trimmed. The heel is supported on the work rest 24 with its top lift in engagement with the top lift rest 22. The crease guide 26 engages the shoe in the crease between the heel and the upper which is frequently called the rand crease. It will be noted that the distance from the top lift to the rand crease is greater at the rear of the heel than at the front or heel breast. Therefore, as the shoe is turned by the operator to present successive portions of the heel to the cutter, the crease guide must yield to the left as the rear of the heel approaches it and then must return to the right as the second side of the heel is trimmed, the crease guide at all times being in engagement with the rand crease. The amount of movement is relatively slight and just equal to the difference in the heel height from front to rear and varies, depending on the shoe size and style.

The arrangement of the links 56 and 70 supporting the carrier 40 and their associated mechanisms permit the crease guide to yield against the force of the spring 84, the positions of the various above-mentioned adjustable members determining the path of movement as now to be described. When the crease guide is in the position ready for use it shrouds the ribbed member 10 the position of which, lengthwise of the cutter shaft 4, depends on the width of the cutters clamped in the cutter head. The cutters are selected to accommodate the height of a heel to be trimmed. In this position the axis C of the stud 30 lies substantially parallel to the axis B of the cutter shaft 4 and a little below it. The bolt 82 is rotated initially so that its eccentric portion 80 acting through the link 70 makes axes B and C parallel. The radius of the arcuate slot 68 is equal to the length

between centers of the link 70; therefore, any adjustment of the bolt 72 in the slot does not affect the parallelism of the axes.

Adjustment of the slide 32 in the carrier when the crease guide is in its starting position moves the crease guide lengthwise toward or away from the ribbed member 10, the cutter size graduations on the slide 30 enabling the operator to set the crease guide in the appropriate position for the particular pair of cutters being used. The stop screw 88 is initially used to make the rough adjustment of the crease guide relative to the cutters and the knurled knob 46 to make the fine adjustment.

By adjusting the bolt 72 in the slot 68 the operator determines the path followed by the crease guide as it moves yielding away from the cutter head in accordance with the style of heel to be trimmed. The most suitable path to be followed for a particular style of heel is determined by trial and error, the slot graduations 78 assisting the operator to obtain a setting shown by experience to be correct. When the machine is used to trim a low heel, the yielding movement of the crease guide is small and the setting of the bolt 72 relatively unimportant.

The arrangement of the carrier 40, the links 56 and 70 and their associated mechanisms which provide for this path of movement is well known and is not described in further detail.

Owing to the involute shape of its periphery, angular adjustment of the crease guide 26 about the axis C of the stud 30 varies the distance between the axis of the cutter head B and that forward shoe engaging portion of the periphery of the crease guide which engages the crease formed between the heel and the upper of the shoe. Therefore, angular adjustment of the crease guide 26 determines how close to the crease the cutters trim the heel.

Fig. 3 is a diagrammatic representation of the shape of the crease guide as seen from the right side of the machine in the position shown in Figs. 1 and 2 when the crease guide is in starting position shrouding the ribbed member 10. An intermediate portion A of the involute portion DAE of the periphery DAEFI of the crease guide 26 is shown turned into the shoe engaging position, this shoe engaging position being in front of and level with the cutter head axis B.

The involute portion DAE is generated by the end of a straight line rolling on a hypothetical circle J which has its center on the axis C of the stud and passes through the axis B of the cutter shaft; thus, the radius of the circle J is equal to the distance between the axes B and C. It will be seen that the shoe engaging portion A of the crease guide lies approximately on the arc GH (shown as a dotted line) which is struck about the axis B of the cutter shaft. Because of this the shoe will remain at a desired distance from the cutters should it engage the crease guide at a point somewhat above or below the axis B of the cutter shaft.

Since the crease guide is adjusted about the axis C and is required, in one position at least, to fit close to the ribbed member 10 (which rotates about the axis B) it is necessary to limit the involute portion DAE to about two-fifths of the periphery of the crease guide, and to limit angular movement of the crease guide (by means of the pin 34) to avoid contacting the ribbed member 10 in one position or another of the crease guide.

Arcuate portions DI and EF of the periphery of the crease guide blend smoothly with, and form continuations of, the involute portion DAE since they may engage the shoe, on occasion, should the operator cause the shoe to contact the crease guide at a point above or below the axis B of the cutter shaft, when the crease guide is set in an extreme angular position.

Thus for any working angular position of the crease guide, the shoe engaging portion of its periphery lies approximately along an arc struck about the axis B of the cutter head, thereby providing a working surface on

which the shoe can be swung without causing it to move appreciably, inwardly or outwardly, radially of the cutter head. Therefore, because the working portion of the crease guide is an involute rather than a series of stepped arcs, as in the prior machines, the shoe may be positioned with maximum accuracy at a desired distance from the axis of the cutter head and the path of the cutting blades. The operator may thus vary by any desired amount, however small, the closeness with which the cutters, as they trim the heel, approach the upper of the shoe.

Having thus described our invention, what we claim as new and desire to secure by Letters Patent of the United States is:

1. In a heel trimming machine having a cutter head rotatable about a first axis and mounting a plurality of cutting blades, a guard attachment shrouding one end of the cutting blades and adjustable about a second axis parallel to and spaced from said first axis, said guard attachment having a shoe engaging periphery in a plane substantially normal to said second axis and formed in the shape of an involute generated by a straight line rolling on a circle having its center on said first axis and passing through said second axis.

2. In a heel trimming machine having a cutter head 25 rotatable about a first axis and mounting a plurality of cutting blades, a guard attachment shrouding one end of

the cutting blades and adjustable about a second axis parallel to and spaced from said first axis, said guard attachment having a shoe engaging periphery in a plane substantially normal to said second axis and formed in the shape of an involute of a circle, and means mounting the guard attachment for yielding movement substantially axially of the cutter head in a predetermined path during trimming.

3. In a heel trimming machine having a cutter head rotatable about a first axis and mounting a plurality of cutting blades, a guard attachment shrouding one end of the cutting blades and adjustable about a second axis parallel to and spaced from said first axis, said guard attachment having a shoe engaging periphery in a plane substantially normal to said second axis and formed in the shape of an involute generated by a straight line rolling on a circle having its center on said first axis and passing through said second axis, and means to adjust said shoe engaging periphery rotatably about said second axis whereby the distance between said shoe engaging periphery and said first axis may be varied.
